CLOSURE OPERATOR

Carl A. Williams, Los Angeles, Calif.

Application February 7, 1950, Serial No. 142,845

4 Claims. (Cl. 268—129)

1

This invention relates to a closure operator and it is an object of the invention to provide an operator of this kind for use in connection with two relatively movable members and wherein means are provided for locking said means in different relations.

It is also an object of the invention to provide an operator wherein desired opening and closing movements may be obtained by the turning of a shaft and wherein means are associated with the shaft for locking a closure member or members in different positions between fully opened and fully closed.

The invention consists in the details of construction and in the combination and arrangement of the several parts of my improved closure operator whereby certain advantages are attained, as will be hereinafter more fully set forth.

In order that my invention may be better understood, I will now proceed to describe the same with reference to the accompanying drawings, wherein:

Figure 1 is a fragmentary view in front elevation illustrating a closure operator constructed in accordance with an embodiment of the invention and employed in connection with upper and lower sashes of a window structure;

Figure 2 is an enlarged detail sectional view taken substantially on the line 2—2 of Figure 1;

Figure 3 is a detail sectional view taken substantially on the line 3—3 of Figure 2, the stile being omitted; and

Figure 4 is an enlarged detail sectional view taken substantially on the line 4—4 of Figure 3.

As illustrated in the accompanying drawings, S denotes a conventional type of stile for a window in which are arranged the usual balance weight for the upper sash A and the lower sash B. As these are all well known a detail description and illustration thereof is believed unnecessary.

The side walls 1 of the stile S at desired locations are provided with the aligned openings 2. Secured by the screws 3 or the like, to the outer face of the outside wall 1 of the stile S, is a plate 4, of a socket member S', which is disposed over the opening 2. The central portion of the plate 4 has rigid therewith a sleeve 5 which snugly fits within the opening 2 of the outside wall 1 and serves as a bearing to rotatably support one end portion of a drum sleeve 6.

The drum sleeve 6 is aligned with a second drum sleeve 7, the outer end portion of which is rotatably supported in a second socket member S" comprised in a sleeve 8 rigid with the central

2

portion of the plate 9. The sleeve 8 snugly fits from without in the opening 2 through the inside wall 1 of the stile S and the plate 9 is secured by the screw 10 or the like, to the outer face of said inside wall 1.

The inner or opposed ends of the sleeve drums 6 and 7 are provided in their walls with the outwardly opening recesses 11 and 12, respectively, which are adapted to be brought into register for a purpose to be hereinafter explained. Extending through the sleeve 7 and into the sleeve 6 is an endwise movable shaft 14 having one end portion extending through the opening 15 in the plate 9 and outwardly beyond the inside wall 1 of the stile. The extended portion of the shaft 14 has operatively engaged therewith a crank 16 to provide a means for rotating the same as desired in either direction.

The shaft 14 is provided with an outwardly and radially disposed blade or key 17 which is normally held within the recess 12 of the sleeve 7 by an expansible member 18. This member 18 is herein disclosed as comprising a coil spring encircling the shaft 14 and interposed between an outwardly facing internal shoulder 19 within the sleeve 7 and the extended extremities of a pin 20 disposed radially through the shaft 14 at a desired distance outwardly from the internal shoulder 19. This pin 20 by contact from within with the plate 9 provides a means to limit the extent of outward movement of the shaft 14 as will also the blade or key 17.

Tightly winding around the drum sleeve 7 is the intermediate portion of a flexible cable 21 one end portion of which extending upwardly and out through the top part of the front wall 22 of the stile S over a conventional pulley 23. The cable extends downwardly from the pulley 23 and is anchored, as at 24 to the top rail 24a of the bottom sash B. The cable 21 has a portion extending downwardly from the sleeve drum 7 and out through the front wall 22 of the stile S in engagement with a conventional pulley 26. The cable extends upwardly from this pulley 26 and is anchored, as at 27, to the lower portion of the adjacent side rail 28 of the lower sash B. By this arrangement, turning the sleeve drum 7 in one direction will raise the lower sash B and said sash will be returned upon reverse rotation of the drum sleeve 7. The drum sleeve 7 will only be rotated in either direction while the blade or key 17 is within the recess 12.

Tightly engaged with the sleeve drum 6 is an intermediate portion of a flexible cable 29. A portion of the cable 29 extends upwardly and

outwardly through the top of the front wall 22 of the stile S over a conventional pulley 30 preferably to one side of the pulley 23 herebefore referred to. The cable 29 extends downwardly from the pulley 30 and is anchored as at 31, to the adjacent stile 36 of the upper sash A.

The cable 29 also has a part that extends downwardly from the sleeve drum 6 and out through the lower portion of the front wall 22 of the stile S in engagement with a conventional pulley 34 preferably to one side of the pulley 26, hereinbefore referred to. The cable 29 extends upwardly from this pulley 34 and is anchored, as at 35, to the lower portion of the adjacent stile 36 of the upper sash A.

Upon desired rotation of the sleeve drum 6, the upper sash A will be either raised or lowered and it is believed to be obvious that the required rotation of the sleeve drum 6 can only be effected when the key or blade 17 is within the recess 11 of the sleeve drum 6. This positioning of the blade or key 17 within the recess 11 is obtained by forcing inwardly the shaft 14 and which movement of the shaft will compress the member or spring 18 to place the same under such tension to assure automatic return of the blade or key 17 into the recess 12 of the sleeve drum 7 while the shaft 14 is relieved of pressure.

The end portion of the sleeve drum 6 within the bearing sleeve 5 is provided with a longitudinally disposed slot 38' which registers with a slot 38 of the bearing sleeve 5. Secured within the sleeve drum 6 at a point substantially diametrically opposed to the inner end of the slot 38', is an end portion of a spring arm 39 of a length to have its opposite or free end extend through the slot 38' and into the slot 38 whereby the sleeve drum 6 is locked against rotation. As the blade or key 17 enters the recess 11 of the sleeve drum 7 upon inward endwise movement of the shaft 14, the inner end of the shaft 14 will contact the spring 39 and flex the same sufficiently to release the spring 39 from within the slot 38 when the blade or key 17 has entered the recess 11 and thus releasing the sleeve drum 6 for desired rotation either to lower or raise the upper sash A.

The blade or key 17 is elongated with its longitudinal axis disposed lengthwise of the shaft 14. This key or blade 17 is also of such length that upon requisite inward movement of the shaft 14, the blade or key 17 may be engaged in both of the recesses 11 and 12 to allow unitary rotation of the sleeve drums 6 and 7 to effect simultaneous opening or closing movements of both sashes A and B. The windings of the flexible members on the sleeve drums 6 and 7 are such to permit such operation.

From the foregoing description it is thought to be obvious that a closure operator constructed in accordance with my invention is particularly well

adapted for use by reason of the convenience and facility with which it may be assembled and operated.

I claim:

1. In an operating means for two members mounted for relative side-by-side endwise movements, a pair of spaced socket type bearings mounted at one side of said members, a pair of aligned sleeves supported at their outer ends in said bearings, a drum mounted on each of said sleeves for rotation therewith, a shaft extending inwardly of one of said bearings through the adjacent of the sleeves and partially through the other sleeve for sliding movements relative thereto, said sleeves having a pair of normally registering recesses opening through their opposed ends, a key carried by said shaft intermediate the ends thereof and movable into engagement with one or the other of said recesses when the shaft is moved endwise in alternate directions, flexible elements having intermediate portions wound on said drums and the end portions of each secured to one of said members, and a hand crank on the outer end of said shaft for imparting turning movements to the shaft when the said key is engaged with one or the other of said recesses whereby the members will be independently moved upon the rotation of a respective one of the drums.
2. The invention as defined in claim 1, with a coil spring encircling said shaft and cooperative therewith to tension the same in an outward direction and maintain said key normally engaged with the recess in the said adjacent one of the sleeves, said spring being partially housed within the latter sleeve and the said one bearing.
3. The invention as defined in claim 1, with the said key having a width sufficient to engage with both of the said recesses when it is desired to impart rotation to said drums simultaneously and likewise move said members relative to each other.
4. The invention as defined in claim 1, with a locking means mounted within the other of said bearings and cooperative with the adjacent end of the other of said sleeves to hold the latter sleeve normally against rotative movements, said locking means being released upon the inward shifting movement of said shaft to engage said key with the recess in the inner end of that sleeve.

CARL A. WILLIAMS.
